UNITED STATES PATENT OFFICE.

JESSE F. MADDEN, OF BROOKLYN, NEW YORK.

THREAD GUIDE.

Application filed November 29, 1922. Serial No. 604,038.

To all whom it may concern:

Be it known that I, JESSE F. MADDEN, a citizen of the United States, residing at Brooklyn, in the county of Kings and State 5 of New York, have invented certain new and useful Improvements in Thread Guides, of which the following is a specification.

My invention relates to thread guides for textile machinery.

10 My object is to provide a device of this character which can be easily threaded and unthreaded by the operator whenever desired, but which cannot become unthreaded by accident.

15 A leading feature of the invention consists of a double hook arrangement at the upper end of the guide, the hooks being spaced from each other and disposed at right angles to the line of travel of the 20 thread, and opening in opposite directions.

The invention consists in certain novel features of construction and arrangement of parts, as will be hereinafter described and claimed, reference being had to the accompanying drawings, in which:—

Fig. 1 is a perspective view showing the device complete.

Fig. 2 is a similar view, but with one of the hooks broken away to show the other 30 hook more clearly.

Fig. 3 is a side plan of one form of the device.

Fig. 4 is an edge view of the same; and, 35 Fig. 5 is a sectional view taken on the line 5—5 of Fig. 4.

The guide is made preferably of porcelain, and in a variety of sizes, with possible slight variations to suit the different textile machines with which it is to be used.

40 Various kinds of guides have been used with textile machinery to guide the many different kinds of threads used in weaving, but there has always been more or less trouble with the thread becoming unthreaded, 45 from the guide at certain times through slackness which is always sure to occur at irregular intervals in the course of weaving, causing an undue amount of breakage and waste, and also a loss of time in re-threading the guides.

50 My object is to provide a thoroughly satisfactory guide free from these objectionable features.

Referring further to the drawings, the 55 invention consists of the lower or body portion 1, having at its upper end a trans-

verse slot 2, which divides said end into two spaced parallel sections 3 and 4. The device is further provided in its upper portion with an elongated vertical opening 5 60 extending therethrough at right angles to said transverse slot and extending upwardly into the lower part of said slot.

The spaced portions 3 and 4 are respectively provided with the similar horizontal slots 6 and 7 leading out in opposite directions from the vertical opening 5 and at the bottom of the transverse slot 2, thereby forming the upper end of the device into two spaced parallel hooks opening in opposite directions from each other.

The transverse slot 2 may be flared at its upper end if desired to render it easier to enter a thread thereinto.

The lower end of the device has a vertical opening 8 for securing the device to the various makes of machines with which it is to be used. A screw or wire may be inserted into said opening, and if desired, the connection may be made rigid by means of cement.

In operation, a thread is entered into the guide by passing a horizontal section thereof down in the slot 2 to the bottom thereof, and then bringing the two ends of the thread through the horizontal slots 6 and 7 into alinement with each other, which will bring them into the vertical opening 5 which forms the eye or traveling space of the guide. It will then be impossible for the thread to become accidentally unthreaded, no matter which way it pulls, or which way it rebounds in the eye,—whether up or down or to one side or the other. If it flies upwardly, it will be rebounded by the upper end of the eye; and the oppositely opening hooks 3 and 4 will prevent it from moving laterally out of the eye in either direction, so that the thread cannot become unthreaded while the device is in operation unless the thread breaks.

Hence it will be seen that I have provided a guide which permits the free and easy passage of the thread therethrough, and which can be quickly and conveniently threaded and unthreaded when desired, but which cannot become unthreaded by accident when in operation.

Having now described my invention, what I claim as new and desire to protect 110 by Letters Patent is:—

1. In a device of the character described,

an elongated body having a transverse slot in its upper end to form said end into two spaced sections, the device also having an elongated opening extending through the same at right angles to said slot, said spaced portions having individual slots leading out in opposite directions from said elongated opening, whereby to form the upper part of said member into two spaced hooks opening at opposite sides of the member.

2. In a device of the character described, an elongated member having means at one end for engaging and holding the same in operative position, said member having a

transverse slot in its upper end dividing said end into two spaced sections, said member also having an elongated opening leading therethrough at right angles to said transverse slot and extending upwardly into said slot, said spaced sections being provided at the bottom of said transverse slot with horizontal slots leading out in opposite directions from said elongated opening, to form the upper part of the guide into two spaced hooks opening at opposite sides of the device.

In testimony whereof I affix my signature.

JESSE F. MADDEN.
